UNITED STATES PATENT OFFICE

2,449,582

PULSATING PNEUMATIC STRATIFIER

Jean Albert Brusset, Blairmore, Alberta, Canada

Application August 3, 1945, Serial No. 608,793

6 Claims. (Cl. 209—468)

1

This invention relates to improvements in process and apparatus for classifying and separating mixtures of particles of material of different specific gravities and particularly to improvements in the apparatus and process described and claimed in my prior United States Patents Nos. 2,241,842, granted May 13, 1941, and 2,353,543, granted July 11, 1944.

In United States Patent No. 2,353,543 there was described and claimed an apparatus for classifying and separating a mixture of solid particles of different specific gravities, in which apparatus two previous reciprocating inclined stepped decks, as supports for two beds of the mixture to be separated, were mounted within a closed compartment, the decks preferably being stepped with the steps facing the higher ends thereof, and there were provided means for establishing successively vacuum and pressure conditions above the decks and means for imparting differential reciprocating motion to the decks in timed relation to the establishment of vacuum and pressure conditions thereabove. The specific means for establishing vacuum and pressure conditions disclosed in Patent No. 2,353,543 comprised a double-acting oscillating wing piston working in a semi-cylindrical shell forming a part of the aforesaid compartment, said wing piston being associated with appropriate means for imparting thereto oscillatory movement the extent of which was variable at the will of the operator whereby to control and/or modify the degree of partial vacuum created by the wing piston or vane.

It is both expensive and difficult to construct a wing piston or vane, of the sort disclosed in Patent No. 2,353,543, sturdy enough to withstand 200 to 300 reversals per minute, in which range of speeds the vane has to operate when the separatory device of the patent is operating at or near its maximum. Moreover, the vacuum-and-pressure construction of the patented device gave a fixed 1-to-1 ratio of periods of vacuum and pressure, whereas it is in many cases desirable to be able to protract the partial vacuum condition, e. g., to modify the ratio to, say, 2 or 3 time units of the partial vacuum condition per 1 unit of the pressure condition. Also, the "shape" of the pulsation effected by the wing or vane of the patented device left something to be desired, in that the partial vacuum increased very rapidly at the start of the vacuum stroke but flattened out as the stroke reached the point of reversal and air leaked through the deck and the bed supported thereon, whereas a gradually rising vacuum with

5 a sharp cut-off at the point of reversal in general gives a pulsation more to be desired.

It is the general object of the present invention to simplify and simultaneously to improve the construction of the apparatus described and claimed in Patent No. 2,353,543. One specific object of the invention is to provide a simpler and less expensive, yet more efficacious, means for establishing successively vacuum and pressure conditions above the reciprocating previous deck. Another inventive object is to improve the shape of the pulsation both as to the vacuum stroke and as to the pressure stroke. A further inventive object is to provide vacuum-pressure means yielding a longer period of vacuum condition with respect to the period of pressure condition. Still other objects of the invention are to provide for improved synchronization of the deck motion with the pulsation created by the vacuum-pressure device; to provide a more positive feed of material to the apparatus; to provide a single deck (instead of the pair necessary in the construction of the patented apparatus) having an improved design; and to provide positive relief 10 valve means for controlling the degree of pressure condition.

Other objects and advantages of the invention will be disclosed in or be apparent from a consideration of the following detailed description 15 of the separation of coal from refuse and with reference to the accompanying drawings which illustrate a preferred embodiment of the invention. In the drawings:

Fig. 1 is a side elevation of the apparatus, with 20 parts in section;

Fig. 2 is an end elevation, with parts in section, on line 2—2 of Fig. 1;

Fig. 3 is a fragmentary view of the upper part 25 of the apparatus illustrated in Fig. 1, showing the relative positions of vane and cylindrical sleeve valve at one instant in the "pressure stroke"; and

Fig. 4 is a chart showing in two graphs values 30 of the vacuum and back pressure portions of the pulsations produced in the apparatus of the present invention and in the apparatus disclosed in Patent No. 2,353,543.

Referring more particularly to the drawings, 35 indicates a horizontally elongated housing at least the upper and central portions of which are surrounded by enclosure 11. Housing 10 is somewhat constricted intermediate its mid-portion and its top, and its top portion is in the form of two equal-radius half-cylinders 14, 15 spaced 40 apart at their upper edges 16, 17 to provide a rel-

atively wide slot opening at the top of the housing. In this upper, open, end of housing 10 are arranged an elongated rotatable cylindrical sleeve member 18 and a vane member 20 having the same radius as sleeve 18, which sleeve 18 and vane 20 are substantially as long as is housing 10 and have a radius very slightly less than that of the half-cylinders 14, 15. Coacting sleeve 18 and vane 20 are mounted on shafts 21, 22, which latter are journaled, in the end walls of housing 10, as indicated at 23, 24, for rotation in substantially the same horizontal plane and are so positioned with respect to each other and to half-cylinders 14, 15 as to function somewhat as a "gear pump" within the latter. That is to say, during that part of each full revolution of members 18 and 20 when the solid segment of vane member 20 is adjacent half-cylinder 15 said members 18 and 20 are so positioned with respect to each other and to half-cylinders 14 and 15 as substantially to seal the slot opening 16, 17 against downward passage of air to space Z, while simultaneously vane member 20 is sweeping trapped air outwardly through slot opening 16, 17 into space U. The positioning of members 18 and 20 illustrated in Fig. 2 represents the end of this stage of operation. 25 indicates a drive pulley mounted on shaft 21 and connected by a suitable belt to the drive pulley of an electric motor 64 for rotating sleeve 18, and 26 indicates a gear wheel (likewise mounted on shaft 21) meshing with a like gear wheel mounted on shaft 22, for rotating vane 20 at a speed, say 200-300 R. P. M., identical with the speed of rotation of sleeve 18 but in an opposite direction (as shown by the arrows in Fig. 2).

As shown in Fig. 2, sleeve 18 has an open segment amounting to about 120°, while vane 20 is provided with a solid segment amounting to a little less than 90°. 18 and 20 are so mounted on their shafts that the motion of the one is synchronized with that of the other, to the end that vane 20 "meshes," as illustrated in Fig. 3, into the open segment of sleeve 18 for a portion of each revolution.

The lower portion of housing 10 is formed into a pair of inverted pyramidal dust hoppers 30, 31 open at their bases. Hoppers 30, 31 are closed at their apices by star extractors 32, 33. The hopper adjacent the high end of the deck is for the collection of mixed dusts of the heavier and lighter components of the mixture being treated, while the hopper adjacent the low end of the deck is for the collection of relatively clean dust of the lighter component of the mixture.

38 represents an inclined pervious deck mounted, for oscillatory movement in its own general plane, on toggle members 40, 41, supported within housing 10. Preferably, deck 38 is formed of perforated sheet material—with perforations of, say, from 16 to 30 mesh—of stepped formation providing slanting faces upwardly inclined toward the high end of the deck (i. e., the left hand end in Fig. 1) and steep, substantially vertical shoulders joining the upper and lower edges of adjacent slanting faces. The deck may, as shown in Fig. 1, extend in a single plane; preferably, however, it is so constructed that a portion (e. g., about a third) of the high end thereof is slightly bent or concaved upwardly from the general plane of the deck, whereby to provide a steeper climb for refuse at the end of its travel and hence a cleaner separation. Oscillatory movement is imparted to deck 38, from motor 64, through eccentric drive 45 mounted outside of housing 10 and

driving crank 46, operating through opening 47 in member 38, to transmit motion to deck 38. Preferably, the deck is advanced relatively slowly in the facing direction of the steps thereof, and is retracted more rapidly.

Deck 38 is substantially as wide as is housing 10 at its broadest mid-portion; it is positioned above dust hoppers 30, 31, and is substantially as long as the two bases of dust hoppers 30, 31 taken together. Beyond either end of deck 38, housing 10 is provided with two substantially vertical delivery chutes, the one, 50, at the high end of the deck, being for the delivery of refuse, and the other, 51, at the low end of the deck, being for the delivery of clean coal. Chutes 50 and 51 are open at their upper ends and are closed at their lower ends by star extractors 52, 53, respectively.

55 represents a substantially horizontal screw conveyor communicating between raw material hopper 56 and the interior of housing 10 above deck 38 for delivering a stream of raw material to the deck at a locus intermediate its ends.

The space within housing 10 above and adjacent deck 38 is called herein "Z," while that within the confines of half-cylinders 14 and 15 is called "Q" and that below deck 38 is called "W." The space between the upper and mid-portions of housing 10 and enclosure 11 is called herein "U." Communication between space U and space W is afforded by a plurality of relief valves "V" spaced along the lower part of housing 10 on either side of the latter. Each of relief valves V is composed of (a) a duct 60 let into the wall of housing 10 and laterally extending into space W and presenting in the latter an orifice 61, and (b) a weighted plate 62, of a size to close orifice 61, pivoted as at 63 to housing 10. Plate 62 is so weighted as to be forced away from orifice 61 when the pressure in space U exceeds some predetermined value (less than 0.50 lb./sq. in. in all cases, and about 0.25 lb./sq. in. on the average).

When vane 20, upon rotation, approaches the constriction in the upper portion of housing 10 it, in conjunction with sleeve member 18, "traps" air in space Q, and upon continued rotation forces at least part of the same through the relatively wide slot 16, 17 and out of housing 10 into space U, thereby creating a partial vacuum or "vacuum condition" in space Z and a corresponding "pressure condition" in space U. Still further rotation of parts 20 and 18—to the meshed position illustrated in Fig. 3—opens the slot 16, 17, permitting flow of air from space U into space Z. The slot remains open until such time as the solid front of sleeve 20, in its continued rotation, approaches half-cylinder 15. By this time sleeve 18 has assumed a position to close the remainder of the passage. A relatively wide slot or port at 16, 17 is desirable in order that air may travel back and forth therethrough with a minimum of lamination.

The synchronized motions of parts 18 and 20 and the position of slot opening 16, 17 assure, for the size of sleeve 18 as illustrated, in space Z a vacuum period of two-thirds and a pressure period of one-third of each full revolution (one-third being the ratio of 120° to 360°). The period of vacuum conditions lasts as long as it takes sleeve 18 to rotate by 240°, the latter being the width of its blank segment which blocks passage of air between spaces U and Z, during which portion of a full revolution member 20 simultaneously is functioning to force trapped air out of

space Q by way of the slot opening 16, 17, into space U, while the back-pressure period corresponds to the 120° rotation during which the empty segment of 19 faces shaft 22 and member 20 simultaneously is in a position remote from half-cylinder 15, as shown in Fig. 3, thus affording a large unrestricted passageway, beneath slot opening 16, 17, for the inrush of air from space U into space Z said movement of air being effected by the momentarily existing differential in air pressures between spaces U and Z. Such relative durations of the vacuum and back-pressure periods of the pulsation can, of course, be modified by changing the length of the full segment of sleeve 19 (with a compensating change in length of the solid segment of vane 20), the theoretical maximum ratio being 3- (for vacuum) to-1 (for back pressure), and the actual maximum ratio being slightly less than 3-to-1. If so desired, the ratio could, of course, be modified in the reverse direction.

For a given apparatus of fixed dimensions, the absolute value of the vacuum producible in space Z above deck 38 is variable by changing the R. P. M. of parts 19 and 20; when they rotate faster there is less time for the leakage of air through deck 38 and the bed of material thereon to reduce the theoretical vacuum which should be created in space Z.

In each pulsation the "vacuum period" is the active period: during the same the stratified clean coal layer (that is to say, the lighter component of the mixture) tends to be lifted away from the refuse (or heavier component) layer, which latter tends to remain in contact with the deck. The so-stratified refuse moves "backward" up the sloping deck following the impulses of the latter, while the clean coal layer moves "forward" and downward in counterflow to the refuse. During the "pressure period" the clean coal is pressed on top of the bed of refuse and travels with the latter: the useful role of this period consists mainly in forcing fine dust (raised during the vacuum period) back down into the bed, in order to maintain the bed in "air-tight" condition. It will be seen, from this exposition, that the pressure period need not be long, as a relatively short blast of back-pressure suffices to press the dust back into the bed; also, that any increase in the relative duration of the vacuum period of the pulsation increases the time per hour devoted to (a) separation of clean coal from refuse and (b) movement of the separated products, in opposite directions, to their respective discharge points. As was noted hereinbefore, I can by means of the present invention prolong the vacuum period—the back-pressure period being constant—up to 3-to-1 and hence can increase the throughput per square foot of deck up to an amount 50% greater than that attainable in the construction described and claimed in Patent No. 2,353,543.

It should be noted, also that the "shape" of the pulsation afforded by the present apparatus is in most cases more to be desired than that afforded by the patented apparatus. The graphs of Fig. 4 show, for the patented apparatus (in solid line) and for the newly invented improved apparatus (in dotted line), the relative duration and time characteristics of the pulsations with regard to their vacuum and back-pressure components. In the case of the pulsation by the patented apparatus, the vacuum condition first increases very fast; then, as the wing approaches the reversal point the vacuum graph flattens out,

as air leaks through the deck and bed. The back-pressure portion of that graph is a little sharper at the conclusion of the pulsation because the bed becomes more and more compact as the pressure condition continues. In distinction to the above, the graph of the pulsation afforded by the present apparatus shows a gradually rising vacuum—due to the constant speed of vane 20; then, at the cut-off corresponding to the unsealing of the slot opening, a sharp drop in the value of the vacuum; and a back-pressure condition wherein the back-pressure very quickly reaches its maximum value, due to the blast of air which rapidly flows from space U to space Z during the interval represented in Fig. 3. With reference to the dotted-line graph of the pulsation afforded by the present apparatus, it is noted that the starting point (left-hand end) of the line denoting vacuum condition represents the point in the full revolution of members 19 and 20 when vane 20 is in a position approximately opposite that shown in Fig. 2, i. e., when rotation of vane 20 has brought the latter adjacent half-cylinder 15 so as to begin to sweep air trapped in the upper part of space Q outwardly through slot 16, 17 into space U. The positions of members 19 and 20 illustrated in Fig. 2 correspond to a point on the dotted line graph relatively close to the crest or "point of reversal." The portion of the dotted line which is below the horizontal line denotes the relatively brief portion of the full cycle when a maximum of air has rushed from space U through slots 16, 17 and past meshed parts 19 and 20 into space Z.

Accordingly, the vacuum and pressure graphs indicate opposed characteristics for the pulsation of the patented apparatus and for the pulsation of the vacuum jig: that of the latter is, in practically all cases, more favorable to classification of the materials according to their specific gravities, as the vacuum gradually rises to maximum value and abruptly falls off to zero: similarly, the relatively strong back-pressure at the beginning of the back-pressure period strikes the bed while the latter is in a distended position and more efficiently drives the dust down into the bed.

Regarding the role of the relief valves V, it should be noted that control of the pressure condition obtaining in space U to a low value is important, because otherwise the consumption of power would materially increase and heating would develop. Relief valves V can be adjusted so that pressure in space U does not exceed one-half or one-fourth lb./sq. in. The function of these valves is made easier by the relatively large volume of space U as compared to the volume of air displaced by vane 20 at each pulsation (the space within U being from 12 to 15 times the volume of air displaced thereto per pulsation): hence, a fairly constant value of pressure in space U minimizes actuation of relief valves V.

It may be noted that the use of a worm conveyor, feeding raw coal from a surge bin or hopper, assures a more positive feed of the material; also, that use of a single deck, instead of the pair of decks employed in the patented apparatus, makes for a simpler and more economical construction, and more economical maintenance, for the same throughput.

The eccentric drive described above and illustrated in the drawing is adequate so long as the proportion of refuse does not exceed, say, 20%: when, however, the relative amount of refuse exceeds about 20% it is advisable to use a differential motion drive (as described and illus-

trated in Patent No. 2,353,543) in order to facilitate the upward and backward travel of the heavy material. In both cases the deck motion must be synchronized with the pulsation, so that the deck travels forward and downward during the sharpest part of the vacuum period, whereby to favor the segregation of the heavy material into the layer adjacent the deck. Synchronization between deck motion and pulsation by means of the common drive motor 64 is much simpler in the case of the present improved apparatus because all mechanical parts are in constant-speed rotation. This latter circumstance also makes for a simpler and cheaper construction of apparatus.

As will be understood, by one skilled in this art, from a consideration of the foregoing description and of the drawing, the apparatus is susceptible to considerable variation without departing from the concepts of the present invention. For instance, it readily will be appreciated that the cylindrical sleeve vane combination need not be as long as is the compartment, it being necessary only that they be of reasonable length and that they be co-extensive with the slot opening or port in the top of the compartment. Also, instead of forming the side walls per se of the compartment into two half-cylinders, as shown in Figs. 1 and 3, the curved surfaces for co-operation with the cylindrical sleeve and intermeshing rotary vane may be arranged within the compartment adjacent the top of the latter.

Accordingly, the invention is to be construed as broadly as is defined in the appended claims.

While the apparatus of the present invention has been specifically described with particular reference to the cleaning of coal, it is to be understood that the same is not limited to that specific use but rather is applicable generally in the dry separation of mixed solid particles according to their specific gravities, e. g., in the dry cleaning of washing plant tailings and similar finely divided lean iron ores, etc.

I claim:

1. In apparatus for classifying a mixture of materials according to specific gravity, a horizontally elongated housing having a slot opening at the top thereof substantially parallel to the longitudinal axis of the housing, a reciprocating inclined pervious deck mounted in said housing intermediate the top and bottom of the latter, intermeshing oppositely rotatable and interacting vane and sleeve members within said housing adjacent to and coextensive with said slot opening and cooperating with the latter to establish successively vacuum and pressure conditions above said deck, and means for imparting reciprocating motion to said deck substantially in the plane thereof in timed relation to establishment of said vacuum and pressure conditions.

2. In apparatus for classifying a mixture of materials according to specific gravity, a horizontally elongated housing having a slot opening at the top thereof substantially parallel to the longitudinal axis of the housing, a reciprocating inclined pervious deck mounted in said housing intermediate the top and bottom of the latter, intermeshing oppositely rotatable and interacting vane and sleeve members within said housing adjacent to and coextensive with said slot opening and cooperating with the latter to establish successively a vacuum condition of relatively long duration and a pressure condition of relatively short duration above said deck, and means for imparting reciprocating motion to said deck substantially in the plane thereof in timed relation

to establishment of said vacuum and pressure conditions.

3. The apparatus defined in claim 1, wherein the vacuum-pressure-establishing means comprises a rotary cylindrical sleeve member having an open segment of greater than 90° but not greater than about 120°, an intermeshing and co-operating rotatable vane having the same radius as said cylindrical sleeve member and provided with a solid segment of approximately 90°, and means for rotating said cylindrical sleeve member and said vane at the same speed but in opposite directions.

4. In apparatus for classifying a mixture of materials according to specific gravity, a horizontally elongated housing having a slot opening at the top thereof substantially parallel to the longitudinal axis of the housing, a substantially gas-tight enclosure surrounding at least the upper portions of said housing, a reciprocating inclined pervious deck mounted in said housing intermediate the top and bottom of the latter, intermeshing oppositely rotatable and interacting vane and sleeve members within said housing adjacent to and coextensive with said slot opening and cooperating with the latter alternately to cause air to be exhausted from the upper portion of said housing through said slot opening and to be stored under pressure within said enclosure and to permit air under pressure to flow from within said enclosure through said slot opening into the upper portion of said housing whereby to establish successively vacuum and pressure conditions above said deck, and means for imparting reciprocating motion to said deck substantially in the plane thereof in timed relation to establishment of said vacuum and pressure conditions.

5. In apparatus for classifying a mixture of materials according to specific gravity, a horizontally elongated housing having a slot opening at the top thereof substantially parallel to the longitudinal axis of the housing, a substantially gas-tight enclosure surrounding at least the upper portions of said housing, a reciprocating inclined pervious deck mounted in said housing intermediate the top and bottom of the latter, intermeshing oppositely rotatable and interacting vane and sealing members within said housing adjacent to and coextensive with said slot opening and cooperating with the latter alternately to cause air to be exhausted from the upper portion of said housing through said slot opening and to be stored under pressure within said enclosure and to permit air under pressure to flow from within said enclosure through said slot opening into the upper portion of said housing whereby to establish successively vacuum and pressure conditions above said deck, and means for imparting reciprocating motion to said deck substantially in the plane thereof in timed relation to establishment of said vacuum and pressure conditions.

6. In apparatus for classifying a mixture of materials according to specific gravity, a horizontally elongated housing having a slot opening at the top thereof substantially parallel to the longitudinal axis of the housing, a substantially gas-tight enclosure surrounding at least the upper portions of said housing, a reciprocating inclined pervious deck mounted in said housing intermediate the top and bottom of the latter, intermeshing oppositely rotatable and interacting impelling and sealing members within said housing adjacent to and coextensive with said slot opening and cooperating with the latter alternately to cause air to be exhausted from the upper portion of

said housing through said slot opening and to be stored under pressure within said enclosure and to permit air under pressure to flow from within said enclosure through said slot opening into the upper portion of said housing whereby to establish successively vacuum and pressure conditions above said deck, and means for imparting reciprocating motion to said deck substantially in the plane thereof in timed relation to establishment of said vacuum and pressure conditions. **10**
